What I claim is as follows:

1. In an engine control system, the combination with an internal-combustion engine having a throttle valve; manual means for controlling the throttle valve; a starting device for the engine; and means for controlling said starting device and said manual means to limit to a partly open position the opening of said throttle by said manual means whereby to prevent racing when the engine becomes self-operative.
2. In an engine control system, the combination with an internal-combustion engine having a throttle valve; manual means for controlling the throttle valve; a starting device for the engine; and means for controlling said starting device and said manual means to limit to a partly open position the opening of said throttle by said manual means whereby to prevent racing when the engine becomes self-operative, said starter controlling means permitting a limited control of said throttle by said manual means.
3. In an engine control system, the combination with an internal-combustion engine having a throttle valve; manual means for controlling the throttle valve; a starting device for the engine including a power device and gearing to connect the same with the engine; and means for controlling the power device for moving certain of said gearing into and out of mechanical connection with the engine and for limiting to a partly open position the opening of the throttle by said manual means.
4. In an engine control system, the combination with an internal-combustion engine having a throttle valve and a gear; manual means for controlling the throttle valve; a starting device including an electric motor and a motor pinion shifting into connection with said engine gear; and means for rendering the motor operative, for moving said pinion into and out of engagement with said engine gear and for limiting to a partly open position the opening of said throttle by said manual means.
5. In an engine control system, the combination with an internal-combustion engine; of means for controlling the speed of operation of the engine; a starting motor normally disconnected from the engine; and means for connecting the starting motor with the engine and for controlling said speed controlling means whereby the engine speed is limited to a value less than maximum.
6. In an engine control system, the combination with an internal-combustion engine having a gear; of a starting motor having a gear connected therewith, means for controlling the speed of operation of the engine; and means for connecting said gears and for controlling said speed controlling means whereby the engine speed is limited to a value less than maximum.
7. In an engine starting system, the combination with an internal-combustion engine having a throttle; of a starting device; means for controlling the throttle including a hand lever and a foot pedal, the movement of the foot pedal permitting the setting of the hand lever to remain undisturbed; and means for rendering the starting device operative and for limiting the movement of the throttle by either the hand lever or the foot pedal to a predetermined partly closed position.
8. In an engine starting system, the combination with an internal-combustion engine having a throttle; of a starting device; normally disconnected gearing between the starting device and engine; means for controlling the throttle including a hand lever and a foot pedal, the movement of the foot pedal permitting the setting of the hand lever to remain undisturbed; and means for connecting said gearing and for limiting the movement of the throttle by either the hand lever or the foot pedal to a predetermined partly closed position.
9. In an engine starting system, the combination with an internal-combustion engine having a throttle; of a starting device; normally disconnected gearing between the starting device and engine; means for controlling the throttle including a hand lever and a foot pedal, the movement of the foot pedal permitting the setting of the hand lever to remain undisturbed; and means for rendering the starting device operative, for connecting said gearing and for limiting the movement of the throttle by either the hand lever or the foot pedal to a predetermined partly closed position.
10. In an engine control system, the combination with an internal combustion engine; of an engine starting device; means for controlling the speed of the engine; and means for rendering the starting device operative to crank the engine and for controlling said speed controlling means whereby the engine speed is limited to a value less than maximum.

In testimony whereof I affix my signature.

UNITED STATES PATENT OFFICE.

KNUT OLOF WILLIAM LINDQUIST, OF CHICAGO, ILLINOIS.

MUSIC-LEAF TURNER.

Application filed October 13, 1919. Serial No. 330,209.

To all whom it may concern:

Be it known that I, KNUT OLOF WILLIAM LINDQUIST, a subject of the King of Sweden, and a resident of the city of Chicago, county 5 of Cook, and State of Illinois, have invented certain new and useful Improvements in Music-Leaf Turners, of which the following is a specification.

My invention relates to improvements in 10 music leaf turners, and has for its object the provision of an improved construction of this character by means of which the separate leaves or sheets of a piece of music may be readily turned by the operator, and which 15 is of simple construction and efficient in operation.

Other objects will appear hereinafter.

The invention consists in the combinations and arrangements of parts hereinafter described and claimed.

The invention will be best understood by reference to the accompanying drawings forming a part of this specification, and in which,

25 Fig. 1, is a partial face view, shown partially in section, of a music leaf turner embodying the invention,

Fig. 2, a vertical section taken through a pump cylinder employed in the construction,

30 Fig. 3, a horizontal section taken on line 3—3 of Fig. 1,

Fig. 4, another horizontal section of the device taken on a different plane and showing 35 the parts in somewhat different relation,

Fig. 5, a section taken on line 5—5 of Fig. 1,

Fig. 6, a section taken on line 6—6 of Fig. 1, and

40 Fig. 7, a partial face view of the device, with parts removed for the sake of clearness.

The preferred form of construction, as illustrated in the drawings, comprises a suitable supporting plate 8, adapted to be supported or arranged on the ordinary music rack of a piano or other suitable support, to hold the leaves or sheets of music in proper position for playing. A central supporting rod 9 is mounted in ears 10 struck outwardly from the body of plate 8, and three leaf carrying arms 11, 12 and 13 are pivoted on the rod 9 to swing freely thereon in substantially horizontal planes. Each of said leaf carrying arms is provided with a suitable clamp 14 adapted and arranged to sup-

port and carry the leaves or sheets of music 15 partially indicated in Fig. 1.

Each of said leaf carrying arms is provided with a spring arm 16 connected by means of a corresponding plate 17 with a 60 corresponding spring 18 secured to the outer face of plate 8, the arrangement being such that the springs 18 exert an initial starting tension tending to start the swinging of said leaf carrying arms in each direction, as 65 will be readily understood.

Two operating arms 19 and 20 are also mounted to swing freely on the rod 9, the arm 19 being mounted on an inner sleeve or hub 21 and the arm 20 being mounted on 70 an outer sleeve or hub 22. A coiled spring 23 is coiled on the sleeve 21, with its ends resting against the respective arms 19 and 20, and arranged to hold said arms normally flat against the face of the plate 8. Sleeve 75 21 carries, at its upper end, a pinion 24, and sleeve 22 similarly carries a pinion 25, as shown. The pinion 24 meshes with a mutilated rack bar caused by forming perforations or openings 26 through a plate 27 in 80 longitudinal alignment with a slot 28, and pinion 25 similarly meshes with a similar mutilated rack bar 29 in alignment with a slot 30 in said plate 27. The arrangement is such that movement of the plate 27 in 85 one direction will cause operative rotation of the sleeve 21 and arm 19 in one direction, and operation of the plate 27 in the opposite direction will cause operative operation of the arm 20 in the opposite direction. 90

The plate 27 is formed as a part of a piston rod 31 carrying a piston 32 positioned substantially centrally in a pneumatic cylinder 33 mounted on the plate 8 as shown. The cylinder 33 is in open communication, 95 through a flexible hose or tube 34, with the lower portion of a pump cylinder 35 which may rest upon the floor or other suitable support. A piston 36 is normally positioned substantially centrally in the cylinder 35 and carries bent guide rods 37 operating in guide tubes 38 on the sides of cylinder 35. The piston 36 is connected by a link 39 with an operating lever 40 fulcrumed at 41, as shown. The lever 40 carries foot pedals 42 and 43 at its opposite ends for convenience in rocking said lever in either direction. The lever 40 is mounted on a tubular stand 44 having a plunger 45 slidable therein and resting upon a compression spring 46 im- 100 105 110

prisoned therein. The lever 40 also bears against the opposite forks 47 of a yoke secured to the upper end of plunger 45, and whereby depression of either end of the lever 40 compresses the spring 46 to effect return of said lever to its central normal position. Such operation of lever 40, when it forces the piston 36 downwardly, forces compressed air into the cylinder 33, and reverse operation of said lever rarefies the air in said cylinder, thus serving to reciprocate the piston 33 therein. As previously indicated, the movement of the piston 33 in one direction or the other serves to operate one or the other of the operating arms 19 and 20. Each of the operating arms 19 and 20 carries a radially slideable plate 48 normally pressed inwardly by means of a spring 49 and provided at its lower inner edge with a latch 50, as shown. Each of the slides 48 also carries on its bottom three notches 52 co-operating with a corresponding stop spring 51 mounted on plate 8, as shown, and tending to hold the corresponding slide 48 in three different radial positions. The leaf carrying arms 11, 12 and 13 are provided with stepped shoulders 53 and 54, as shown, said shoulders being adapted and arranged to assume overlapping relations with respect to each other, as best indicated in Figs. 4 and 7, said shoulders being set in the operative paths of the latches 50 and co-operating therewith. Each of the slides 48 carries a trigger plate 55 pivoted at 56 and normally held in depressed position by means of a spring 57, each of said plates being provided with an outer cam surface 58, inclined as shown, and adapted and arranged to operate on the corresponding shoulders 53 or 54, as the case may be. The arrangement is such that as each leaf carrying arm swings outwardly from either position adjacent the plate 8, the corresponding trigger 55 idly yields to permit of free passage, but as each of said leaf carrying arms swings inwardly to operative relation against plate 8, the corresponding cam surface 58 is engaged by the corresponding shoulder 53 or 54, as the case may be, and the corresponding slide 48 forced outwardly by said inward movement of the corresponding leaf carrying arm, the overlapped or stepped relations of said shoulders serving to cause successive progressive outward movements of said latch plates 48. The outer movement of the slide 48 is effected by the inclined plane action of the cam surface 58 on the corresponding shoulder 53 or 54. Each of the arms 19 and 20 also carries a spring-held latch pawl 59, arranged to engage teeth or notches 60 in a bar 61 secured to the side of the corresponding slide 48. Each of the pawls 59 also carries a depending finger 62 adapted to contact with the plate 8 at the end of each inward move-

ment of the corresponding operating arm, and thus release the corresponding slide 48 for radial movement. The arrangement is such that upon each outward movement of each operating arm 19 or 20, as the case may be, the corresponding latch 50 is in normal position to engage the outermost shoulder 53 or 54, as the case may be, and carry the corresponding leaf carrying arm around with it through its operative swing, and whereby it will be observed that the music leaves may be readily turned. As each leaf carrying arm reaches the end of its swinging movement, it encounters the corresponding trigger 55, forcing the corresponding plate 48 outwardly to set the corresponding latch 50 for engagement of the shoulder 53 on the corresponding leaf carrying arm, so that the corresponding latches 50 are always in position to engage the corresponding shoulder on the leaf carrying arm which has last been operated, so that the last arm operated will be the first to be returned under normal conditions, and whereby, it will be observed, the operator may readily operate the device to turn the sheets of music in the proper manner for playing and return them in the same order. When it is desired to turn a plurality of sheets at the same time, as in returning the sheets after use of the same, the corresponding arm is first given an initial but only partial operation to correspond with the number of sheets it is desired to turn simultaneously. Upon each of such partial operations, the corresponding slide 48 will be released and moved inwardly in substantially the same manner when it is desired to turn a single sheet, as herein set forth to engage the next lower leaf carrying arm, and whereby the device may be readily set to turn all or a part of the sheets thereon simultaneously.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having described my invention, what I claim as new and desire to secure by Letters Patent is:—

1. A music leaf turner comprising a support; a plurality of leaf carrying arms pivotally mounted on said support; leaf clamps on said arms; two swinging operating arms mounted coaxially with said leaf carrying arms; trigger mechanisms radially slidably mounted on said operating arms arranged to automatically engage said leaf carrying arms and swing the same in opposite directions; means for varying the radial posi-
